(57) **CLAIM**

I claim the ornamental design for a mask, as shown and described.

DESCRIPTION

FIG. 1 is a perspective view of a mask, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings show stitching in the mask which form a part of the claimed design.

1 Claim, 7 Drawing Sheets
